(57) **CLAIM**

The ornamental design for a seat of baby carriage as shown and described.

DESCRIPTION

FIG. 1 is a perspective view of a seat of baby carriage showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another perspective view thereof showing a using condition with a baby carriage.

The broken lines in FIG. 8 depicting a body carriage illustrate environment. All other broken lines depict portions of the seat of baby carriage. None of the broken lines form any part of the claimed design.
